UNITED STATES PATENT OFFICE.

THOMAS WILTON HAND, OF SHEFFIELD, ENGLAND, ASSIGNOR TO DAVY BROTHERS, LIMITED, OF SHEFFIELD, YORK, ENGLAND.

STEAM HYDRAULIC INTENSIFIER.

1,331,991.

Specification of Letters Patent. Patented Feb. 24, 1920.

Application filed December 10, 1918. Serial No. 266,026.

To all whom it may concern:

Be it known that I, THOMAS WILTON HAND, a subject of the King of Great Britain, residing at Sheffield, in the county of York, England, have invented new and useful Improvements in and Connected with Steam Hydraulic Intensifiers, of which the following is a specification.

This invention relates to hydraulic intensifiers worked by elastic motive fluid (hereinafter, for the sake of convenience, referred to as "steam"), the object of the invention being to provide what may be termed a compound steam hydraulic intensifier, that is to say, an intensifier with two or more steam cylinders adapted to utilize the steam expansively in such manner that, when the hydraulic forging press, shears, or other apparatus actuated by the intensifier is required to work under relatively light load or equivalent conditions, the intensifier can be made to operate substantially as a compound steam engine, whereas, when the press or other apparatus is required to work under conditions of full or relatively heavy load, the intensifier can be made to operate with high steam pressure in what is normally the low-pressure steam cylinder.

Reference is to be had to the accompanying drawings, wherein Figure 1 is a somewhat diagrammatic side elevation illustrating one form of the invention as applied to a steam hydraulic intensifier having two steam cylinders, the steam and hydraulic cylinders with their supports being all shown in axial section; while Fig. 2 is a view similar to Fig. 1 but showing a modified arrangement of steam connections adapted to enable the maximum pressure to be obtained from the apparatus. Figs. 3 and 4 show, to a larger scale and partly in section, an "automatic" steam stop-valve which may be employed as indicated in Fig. 2, the valve being viewed, in Figs. 3 and 4 respectively, in two directions at right angles to one another.

Referring first to Fig. 1, 11 is the hydraulic cylinder, which is mounted at 12 in the lower member of an open frame or stool 13, the axis of the cylinder being arranged vertically and the hydraulic ram 14 being adapted to perform its working stroke in

the upward direction. A steam cylinder 15 of relatively large diameter, is mounted 55 upon the stool 13 in axial alinement with the hydraulic cylinder 11, the upper member 16 of the stool constituting the bottom cover of the cylinder 15. A steam cylinder 17 of relatively small diameter is mounted 60 above and in axial alinement with the cylinder 15; an open frame or stool 18, which is interposed between the cylinders 15 and 17, having a lower member 19 which constitutes the top cover of the cylinder 15 and an 65 upper member 20 which constitutes the bottom cover of the cylinder 17. Pistons 21 and 22, fitted to reciprocate in the respective steam cylinders 15 and 17, are connected by an axially-extending piston-rod 70 23 which passes through stuffing boxes 24 and 25 provided respectively in the lower and upper members 19 and 20 of the stool 18. The maximum effective stroke is the same for both steam pistons 21 and 22 and 75 also for the hydraulic ram 14, which is coupled to the lower steam piston 21 so as to move as one with both pistons 21 and 22. For this purpose a cross-head 26 on the lower end of the ram 14 is connected with 80 the piston 21 by a pair of side rods 27 which extend, at opposite sides of and parallel with the ram 14, through guides 28 in the lower member of the stool 13 and through stuffing-boxes 29 in the bottom cover 16 of 85 the cylinder 15.

In the example illustrated, the steam inlet and exhaust valves of both the steam cylinders are to be understood as double-seat "drop" valves of usual construction; 90 the steam inlet- and-exhaust port 30 of the larger cylinder 15 communicating both with the inlet valve 31 and also with the exhaust valve 32, while the steam inlet- and exhaust-port 35 of the smaller cylinder 17 95 communicates both with the inlet valve 33 and also with the exhaust valve 34. The high-pressure steam supply pipe 36 is on the one hand permanently connected, by a pipe 37, with the inlet valve 33 of the cylinder 17, and on the other hand is connected with the inlet valve 31 of the cylinder 15 by a pipe 38 provided with a stop-valve 39, (which is shown as an ordinary screw-down valve). The exhaust valve 32 of the cylinder 15 is connected with the main exhaust 100 105

pipe 40 while the exhaust valve 34 of the cylinder 17 is connected, by a pipe 41, with a steam receiver 42 which in turn is connected, by a pipe 43, with the pipe 38 leading to the 5 steam inlet valve 31 of the cylinder 15.

In addition, the upper end of the cylinder 15 is connected, by a pipe 44, with the main exhaust pipe 40; and the upper end of the cylinder 17 is closed, and connected, by 10 a pipe 45, with the receiver 42.

All the steam inlet and exhaust valves 31, 32, 33, 34, are controlled concurrently, and in the same sense for the valves of both cylinders 15 and 17, on the one hand manually by means of a single handing-lever, and on the other hand automatically by means of hunting-gear adapted to cause the supply of steam to both cylinders to be cut off, during each working stroke of the intensifier, 20 at a point corresponding to the angular position wherein for the time being the handing-lever is held.

For the purpose of effecting the manual control of the valves, the handing-lever 25 46, which is fulcrumed at a fixed point 47, has an arm 48 coupled by an upright rod 49 to the longer arm of what may be termed the "main" lever 50 in each of the respective sets of valve-actuating mechanism 30 appertaining to the steam cylinders 15 and 17. The two sets of valve-actuating mechanism, which are substantially identical in construction, comprise in each case the aforesaid "main" lever 50, which is substantially horizontal and is fulcrumed at a fixed 35 point 51 at a level considerably above the valves 31 and 32, or 33 and 34; a "floating" lever 52 which is connected by one end to the shorter arm of the main lever 50 and 40 by the opposite end to an intermediate point in the upper section of an upright link 71 formed in two sections which are coupled together by a pin-and-slot connection 71^a, the lower end of the lower section of this 45 link being connected to the spindle 57 of the exhaust valve 32 or 34; and a substantially horizontal "rocking" lever 53 which is fulcrumed at a fixed point 54 beneath the level 50 of the main lever 50 and floating lever 52; this rocking lever being coupled at one end 55 to the spindle 55 of the steam inlet valve 31 or 33 by a pin-and-slot connection 56, at the opposite end to an intermediate point in the lower section of the link 71 by a 60 pin-and-slot connection 59, and, at a point between said connection 59 and the fulcrum 54, to an intermediate point in the floating lever 52 by means of an upright link 58.

The hunting-gear for effecting the automatic control of the valves is actuated by an upright, upwardly-tapering cam-bar 60 fixed at 61 to, and extending upward from, the cross-head 26 and having one edge 62 inclined to the direction of motion of the bar 65 while the opposite edge, which is parallel

to said direction, is guided by contact with a stationary roller 63. Against the inclined edge 62 of this cam-bar, bears a roller 64 carried by one limb of a three-armed lever 65 which is fulcrumed at a fixed point 66, contact between the roller and cam-bar being insured by a counterweight 67 suspended from a second limb of the lever 65. A third limb of the same lever is coupled by an upright rod 68 to one arm of what may be 70 termed the "secondary" lever 69 (as distinguished from the "main" lever 50) of the valve-actuating mechanism appertaining to each steam cylinder 15 and 17; each "secondary" lever 69, which is fulcrumed 80 at a fixed point 70 above the level of the floating lever 52, having its other arm connected to the upper end of the link 71 and thus to that end of the corresponding floating lever 52 which is remote from the main 85 lever 50.

In the drawing all the working parts are shown in their resting positions, the hydraulic ram 14 and the steam pistons 21 and 22 being at the lowest limit of their stroke, the valves 31, 32 and 33, 34 being closed, and the handing-lever 46 being in its mid or neutral position, while the stop-valve 39 is shut. In operation, assuming high-pressure steam to be admitted through 95 the connection 36 to the pipe 37, or (if the stop-valve 39 be open) to both the pipes 37 and 38, the handing-lever 46 is oscillated toward the right or toward the left of its neutral position according as the intensifier 100 is required to perform a working (i. e. an upward) stroke or a return (i. e. a downward) stroke consequent on the opening of the steam inlet valves 31 and 33, or of the steam exhaust valves 32 and 34.

Let it now be supposed that the intensifier is required to work under relatively light load or equivalent conditions;—at starting, the stop valve 39 being closed the first time the handing-lever 46 is moved toward the right of its neutral position, although both the inlet valves 31 and 33 will be opened while the exhaust valves 32 and 34 remain closed, yet the absence of steam between the exhaust valve 34 of the smaller 115 and the inlet valve 31 of the larger steam cylinder will prevent the larger piston 21 from bearing any share in the work performed at the first upward stroke; but, high-pressure steam being admitted beneath the smaller piston 22, both pistons will rise and will carry upward along with them the ram 14 so that water will be expelled from the hydraulic main pressure pipe 72 to the forging press, shears, or other apparatus (not shown) which is actuated by the intensifier.

As the pistons and ram reach a point in their upward stroke corresponding to the angular position in which for the time being 130

the handing-lever is held, the action of the hunting-gear will cause the inlet valves 31 and 33 to close, so that the upward movement will be arrested and the pistons and 5 ram will be supported by the steam beneath the smaller piston 22. If the handing-lever 46 be now moved toward the left of its neutral position, the inlet valves 31 and 33 will remain closed but the exhaust valves 10 32 and 34 will be opened, with the result that the pistons and ram will descend by gravity; the piston 22 expelling the steam from the cylinder 17 into the receiver 42 by way of the pipe 41, while at the same 15 time equilibrium of pressures above and beneath the respective pistons is insured by the pipes 44 and 45. Next time the handing-lever 46 is moved toward the right of its neutral position, not only will the consequent opening of the inlet valve 33 admit 20 high-pressure steam beneath the smaller piston 22 as before, but the opening of the inlet valve 31 will admit steam from the receiver 42 beneath the larger piston 21 by 25 way of the pipes 43 and 38, with the result that the steam which had previously done duty at high pressure in the smaller cylinder 17 will now act expansively in the larger cylinder 15, the piston 21 in which will 30 therefore coöperate with the piston 22 in raising the ram 14 and producing hydraulic pressure in the cylinder 11 and pipe 72.

In practice, the hydraulic pressure obtained by using expansively in the larger 35 steam cylinder 15 the steam exhausted from the smaller steam cylinder 17, would preferably be equal to (say) about two-thirds of the load on the press or other hydraulic apparatus when full-pressure steam is admitted to the smaller steam cylinder; lighter 40 loads being met by throttling the supply of steam to the smaller cylinder.

If the intensifier be required to work under relatively heavy load or equivalent 45 conditions, the stop-valve 39 is opened so as to allow live steam to gain access to the inlet valve 31 of the larger steam cylinder, with the result that each time the handing-lever 46 is moved toward the right of its 50 neutral position high-pressure steam will be admitted not only beneath both pistons 21 and 22 but also above the piston 22 by way of the pipe 43, receiver 42, and pipe 45; so that while the intensifier will now work 55 under the increased effective steam pressure due to the larger area of the lower piston 21, the upper piston 22 will be rendered inoperative owing to equilibrium of pressures being established upon its opposite sides. 60 In order to obtain the highest possible pressure, it is necessary, while admitting live steam beneath both pistons 21 and 22, to prevent such steam from gaining access to the smaller cylinder 17 above its piston 22; 65 for which purpose, for the time being, the

receiver 42 must be isolated from the pipes 41, 43, and 45, and the pipes 41 and 45 connected to the main exhaust pipe 40.

An arrangement for enabling this to be done is illustrated in Figs. 2 to 4, which also 70 show a device which may be used, if desired, for the purpose of admitting live steam beneath the pistons of both steam cylinders either automatically on the hydraulic pressure reaching the maximum attainable by the use of the apparatus as a compound intensifier, or at any other time 75 at will.

In Fig. 2, the hydraulic cylinder 11 and ram 14, the steam cylinders 15 and 17 with 80 their inlet and exhaust valves 31, 32 and 33, 34, as well as the handing-lever 46 and the rest of the mechanism for operating said valves, are all as already described and are denoted by the same reference symbols, so 85 that the explanation of the arrangement and operation of these parts need not be repeated.

In Fig. 2, however, the high-pressure steam supply pipe 36, which is on the one hand permanently connected, by a pipe 37, 90 with the inlet valve 33 of the smaller steam cylinder 17 as before, is on the other hand connected with the inlet valve 31 of the larger steam cylinder 15 by a pipe 73 in which is interposed a valve 74 (hereinafter 95 described in detail) which is normally closed but which is adapted to open automatically on the hydraulic pressure in the cylinder 11 and hydraulic main pressure pipe 72 reaching the maximum attainable by the use of 100 the apparatus as a compound intensifier as already set forth. The valve 74 is also provided with means whereby it may be opened, and kept open, manually when desired, as for example when the development of the 105 maximum hydraulic pressure is required to continue during a considerable period.

The steam receiver 42, which is permanently connected with the upper end of the smaller steam cylinder 17 by a pipe 45 as 110 before, is connected with the pipe 73 (and therefore with the inlet valve 31 of the larger steam cylinder 15) by a pipe 75 which is controlled by a stop-valve 76, which is shown as an ordinary screw-down valve. The exhaust valve 34 of the smaller steam cylinder 17 discharges directly into the receiver 42 by a pipe 41 as before: while a branch 77 from this pipe 41, controlled by a stop-valve 78 (shown as an ordinary screw-down valve) 115 communicates with the main exhaust pipe 40 leading from the exhaust valve 32 of the larger steam cylinder 15. The pipe 44 which, as before, connects the upper end of the cylinder 15 permanently with the main 120 exhaust pipe 40, is shown in Fig. 2 (for the sake of convenience) as leading from said cylinder to a point in the pipe 77 between the main exhaust pipe and the stop-valve 78. 125

In normal expansive working (i. e. when 130

the steam exhausted from the smaller steam cylinder 17 is allowed to pass into and act expansively in the larger steam cylinder 15), the valve 76 is kept open and the valve 78 is 5 kept closed, while the "automatic" valve 74 does not open. In these circumstances, during each upward stroke of the steam pistons 21 and 22, high-pressure steam gains access from the pipe 36 to the smaller steam cylinder 17 alone, by way of the pipe 37 and the 10 inlet valve 33 of said cylinder, while at the same time the steam which was discharged from the cylinder 17 through its exhaust valve 34 during the preceding downward 15 stroke of the piston 22, and which had entered the receiver 42 by the pipe 41, passes thence to the inlet valve 31 of the larger steam cylinder 15 by way of the valve 76 and pipes 75 and 73. On the hydraulic 20 pressure developed in the cylinder 11 the hydraulic main pressure pipe 72 reaching the maximum attainable with such expansive working, the valve 74 opens automatically so that now, during each upward stroke 25 of the steam pistons 21 and 22, high-pressure steam passes not only into the lower end of the smaller steam cylinder 17, but also into the lower end of the larger steam cylinder 15 by way of the valve 74 and pipe 73. At the 30 same time, however, high-pressure steam gains access to the upper end of the smaller cylinder 17 by way of the pipe 75, valve 76 (which is open), receiver 42, and pipe 45, so that although the intensifier will now work 35 under the increased effective steam pressure due to the larger area of the lower piston, the upper piston 22 will be rendered inoperative as described with reference to the operation, in similar circumstances, of the arrangement illustrated in Fig. 1. The higher 40 hydraulic pressure developed as the result of the opening of the valve 74 may (if desired) be maintained for an indefinite time, or may be brought about at any moment (during 45 normal expansive working when required) by opening the valve 74 manually.

In the event of the maximum possible hydraulic pressure required to be obtained, it is necessary, while admitting high-pressure 50 steam beneath both pistons 21 and 22, to exclude such steam from above the smaller piston 22; for which purpose the valve 74 must be kept open by hand, the valve 76 closed, and the valve 78 opened.

55 In these circumstances, during each upward stroke of the steam pistons 21 and 22, high-pressure steam gains access from the pipe 36 both to the lower end of the smaller cylinder 17 by way of the pipe 37 and also to the lower end of the larger cylinder 15 by way of the valve 74 and pipe 73, while during each downward stroke of the pistons, exhaust steam is discharged to the main exhaust pipe 40 not only directly from the 60 larger cylinder 15 as before but also from

the smaller cylinder 17 by way of the pipe 41, valve 78, and pipe 77. It will be seen that, so long as the valve 76 is closed and the valve 78 is open, the upper end of the cylinder 17 is cut off from the main steam 70 supply pipe 36, but remains constantly in communication with the exhaust pipe 40 by way of the pipe 45, receiver 42, pipe 41, valve 78, and pipe 77.

The construction and operation of the 75 "automatic" valve, as illustrated in Figs. 3 and 4, are as follows:—The casing 74 of the valve has at one end an inlet 79 leading from the high-pressure steam supply pipe 36 into the upper part 80 of the valve-chamber, and at the other end an outlet 81 leading from the lower part 82 of the valve-chamber to the pipe 73 which communicates with the inlet valve 31 of the larger steam cylinder 15; while communication between 85 the upper and lower parts 80 and 82 of the valve-chamber is controlled by the valve proper 84, which is a vertically working, double-beat, unbalanced drop-valve adapted to close in the downward direction, and 90 whereof the upper seating 83 is of larger diameter than the lower seating 85 so that the valve has a constant tendency to close under the steam pressure admitted to the upper part 80 of the valve-chamber. The 95 valve-spindle 86, which extends upward, is connected to a point near the middle of the length of a substantially horizontal lever 87 fulcrumed at 88 and adjustably loaded at its free extremity by means of a weight 89. 100 Near the fulcrum 88, the lever 87 has a pin-and-slot connection at 90 with a link 91 whereby it is coupled to the upper end of a small hydraulic ram 92 fitted to work vertically in a stationary hydraulic cylinder 93, the ram 92 being adapted to perform its operative stroke in the upward direction; while the cylinder 93 is in permanent communication with the hydraulic main pressure pipe 72 (Fig. 2) by way of a branch 110 pipe 94. Near its free extremity the lever 87 has a pin-and-slot connection at 95 with the upper end of an upright rod 96 through which the lever can be manually actuated, the lower end of the rod 96 being coupled 115 to an arm 97 fast on the horizontal fulcrum-shaft 98 of a hand-lever 99 which, as indicated in Fig. 2, is arranged in convenient proximity to the main handing-lever 46 whereby the strokes of the intensifier 120 are controlled.

The constant tendency of the "automatic" valve to close under steam pressure is assisted by the weight 89 acting through the lever 87; the total force which thus acts 125 downward upon the valve being just sufficient to counteract the upward effort exerted upon the lever 87 by the hydraulic ram 92, so long as the hydraulic pressure in the cylinder 93 is slightly below the maximum 130

limit attainable by the use of the apparatus as a compound intensifier. Upon the hydraulic pressure in the cylinder 11 of the intensifier (and therefore also in the pipes

5 72 and 94 and in the cylinder 93) reaching the maximum limit attainable by the use of the apparatus as a compound intensifier, the hydraulic pressure in the cylinder 93 becomes sufficient to enable the upward effort of the ram 92 upon the lever 87 to overcome the combined downward effort of the weight 98 and of the steam pressure tending to close the "automatic" valve, with the result that this valve now opens and 10 permits high-pressure steam to gain access to the larger steam cylinder 15. The pin-and-slot connection at 95 permits of the automatic upward movement of the lever 87 being performed without affecting the 15 rod 96 and hand-lever 99.

20 If, while the intensifier is working expansively, it is desired to admit high-pressure steam to the larger steam cylinder 15, this may be effected manually by so operating the hand-lever 99 as to raise the lever 87 and open the "automatic" valve against the combined downward effort of the weight 89 and of the steam pressure tending to close the valve; the pin-and-slot connection 25 at 90 permitting of the upward movement of the lever 87 being performed without affecting the hydraulic ram 92.

30 In the same way the "automatic" valve, after being opened by hydraulic pressure on the maximum limit of such pressure being reached during normal expansive working, may be kept open for an indefinite period by the use of the hand-lever 99.

35 It will be obvious that any convenient means may be provided for enabling the 40 stop-valves 76 and 78 (Fig. 2) to be manually controlled from a point in convenient proximity to the hand-levers 46 and 99, if desired. These stop-valves might also be 45 controlled through the medium of a power relay.

50 Inasmuch as the receiver 42 constitutes, in effect, merely a local enlargement of the pipes with which it is immediately connected, it will be obvious that the provision 55 of a structurally distinct receiver (such for example as that shown at 42 in the drawing) is not essential, and that the pipes which are shown as connected together through the medium of the receiver might, if of sufficient capacity, be made continuous with one another as a single pipe, the pipe 45 being joined to the remainder of the pipe-system at a suitable branch.

60 In the foregoing description, the elastic motive fluid operating in the intensifier is for the sake of convenience referred to as "steam," but it will be evident that other elastic motive fluid (such as compressed air 65 for example) may be used; and hence it is

to be understood that both throughout the description and in the appended claims the term "steam" is to be interpreted as including any kind of elastic motive fluid.

I claim

1. In a hydraulic intensifier operated by elastic motive fluid, the combination with a pair of hydraulic elements comprising a hydraulic cylinder and a ram coöperating therewith, of a plurality of cylinders located 70 in coöperative relation, pistons in said cylinders coupled to one another and to the movable member of said pair of hydraulic elements whereby said pistons and movable member are concurrently operated, means 75 controlling the admission of motive fluid at the maximum pressure to one of said cylinders, a connection leading from the rear or inlet end of said cylinder to the rear of another of said cylinders, means controlling 80 the discharge of the motive fluid exhausted from the rear of said first named cylinder to the rear of said other cylinder and mechanism for actuating all of said controlling means in coöordination with one another. 90

2. In a hydraulic intensifier operated by elastic motive fluid, the combination with a pair of hydraulic elements comprising a hydraulic cylinder and a ram adapted to coöperate therewith, of a plurality of elastic 95 fluid cylinders of progressively increasing diameters, pistons fitted to reciprocate in the respective elastic fluid cylinders and coupled to one another and to the movable member of said pair of hydraulic elements, whereby said pistons and movable member are concurrently operated, passages and valves thereon for admitting elastic motive fluid at the maximum working pressure to the cylinder of least diameter, for leading the motive 100 fluid exhausted from each cylinder of lesser diameter to each cylinder of next larger diameter, and for discharging the motive fluid exhausted from the cylinder of largest diameter respectively, and mechanism for actuating all of said valves in coöordination with one another. 105

3. In a hydraulic intensifier operated by elastic motive fluid, the combination with a pair of hydraulic elements comprising a 115 hydraulic cylinder and a ram adapted to coöperate therewith, of a plurality of elastic fluid cylinders of progressively increasing diameters, pistons fitted to reciprocate in the respective fluid cylinders and coupled to one another and to the movable member of 120 said pair of hydraulic elements, passages and valves thereon for admitting elastic motive fluid at the maximum working pressure to the cylinder of least diameter, for leading the motive fluid exhausted from each cylinder of lesser diameter to each cylinder of next larger diameter and for discharging the motive fluid exhausted from the cylinder of largest diameter respectively, mechanism 130

for actuating all of said valves in coördination with one another, and a receiver for elastic motive fluid interposed, in each passage connecting two cylinders, between the 5 exhaust valve of the smaller and the inlet valve of the larger cylinder.

4. In a hydraulic intensifier operated by elastic motive fluid, the combination with a pair of hydraulic elements comprising a 10 hydraulic cylinder and a ram adapted to coöperate therewith, of a plurality of elastic fluid cylinders of progressively increasing diameters, pistons fitted to reciprocate in the respective elastic fluid cylinders and coupled 15 to one another and to the movable member of said pair of hydraulic elements, whereby said pistons and movable member are concurrently operated, passages and valves thereon for admitting elastic motive fluid at 20 the maximum working pressure to each motive fluid cylinder, for leading the motive fluid exhausted from each cylinder of lesser diameter to each cylinder of next larger diameter, and for discharging the motive 25 fluid exhausted from the cylinder of largest diameter respectively and mechanism for actuating a plurality of said valves in coördination with one another.

5. In a steam hydraulic intensifier, the 30 combination with a pair of hydraulic elements comprising a hydraulic cylinder and a ram adapted to coöperate therewith, the members of said pair having their common axis arranged vertically and the one member being stationary while the other is adapted to perform its working stroke in the upward direction, of steam cylinders of relatively large and relatively small diameter mounted in axial alinement with one 35 another and with the members of the pair of hydraulic elements, single-acting pistons fitted to reciprocate in the respective steam cylinders, an axially-extending piston-rod attached to both of said pistons, a crosshead 40 on the movable member of the pair of hydraulic elements, rods attached eccentrically to one of the steam pistons and to said crosshead and extending parallel to the cylinder axis, whereby said movable member and 45 said pistons are concurrently actuated, passages and valves thereon for admitting high-pressure steam to the lower end of the smaller steam cylinder, for leading the steam exhausted from the lower end of said 50 cylinder to the lower end of the larger steam cylinder, and for discharging the steam exhausted from the lower end of the last-mentioned cylinder respectively, and mechanism for actuating all of said valves in coördination 55 with one another.

6. In a steam hydraulic intensifier, the combination with a pair of hydraulic elements comprising a hydraulic cylinder and a ram adapted to coöperate therewith, the 60 members of said pair having their common

axis arranged vertically and the one member being stationary while the other is adapted to perform its working stroke in the upward direction, of steam cylinders of relatively large and relatively small diameter 70 mounted in axial alinement with one another and with the members of the pair of hydraulic elements, single-acting pistons fitted to reciprocate in the respective steam cylinders, an axially-extending piston-rod 75 attached to both of said pistons, a crosshead on the movable member of the pair of hydraulic elements, rods attached eccentrically to one of the steam pistons and to said crosshead and extending parallel to the cylinder axis, 80 passages and valves thereon for admitting high-pressure steam to the lower end of the smaller steam cylinder, for leading the steam exhausted from the lower end of said cylinder to the lower end of the larger steam cylinder, and for discharging the steam exhausted from the lower end of the last-mentioned cylinder respectively, mechanism for actuating all of said valves in coördination with one another, and a 85 steam receiver interposed in the passage leading from the exhaust valve of the smaller steam cylinder to the inlet valve of the larger steam cylinder.

7. In a steam hydraulic intensifier, the 90 combination with a pair of hydraulic elements comprising a hydraulic cylinder and a ram adapted to coöperate therewith, the members of said pair having their common axis arranged vertically and the one member being stationary while the other is adapted to perform its working stroke in the upward direction, of steam cylinders of relatively large and relatively small diameter 95 mounted in axial alinement with one another and with the members of the pair of hydraulic elements, single-acting pistons fitted to reciprocate in the respective steam cylinders, an axially-extending piston-rod 100 attached to both of said pistons, a crosshead on the movable member of the pair of hydraulic elements, rods attached eccentrically to one of the steam pistons and to said crosshead and extending parallel to the cylinder axis, whereby said movable member and said 105 pistons are concurrently actuated, passages and valves thereon for admitting high pressure steam to the lower end of the smaller steam cylinder, for leading the steam exhausted from the lower end of said cylinder to the lower end of the larger steam cylinder, and for discharging the steam exhausted from the lower end of the last-mentioned cylinder respectively, mechanism for 110 actuating all of said valves in coördination 115 with one another, a passage for admitting high-pressure steam to the lower end of the larger steam cylinder, and a stop-valve on said passage.

8. In a steam hydraulic intensifier, the 120

- combination with a pair of hydraulic elements comprising a hydraulic cylinder and a ram adapted to coöperate therewith, the members of said pair having their common 5 axis arranged vertically and the one member being stationary while the other is adapted to perform its working stroke in the upward direction, of steam cylinders of relatively large and relatively small diameter 10 mounted in axial alinement with one another and with the members of the pair of hydraulic elements, single-acting pistons fitted to reciprocate in the respective steam cylinders, an axially-extending piston rod 15 attached to both of said pistons, a crosshead on the movable member of the pair of hydraulic elements, rods attached eccentrically to one of the steam pistons and to said crosshead and extending parallel to the cylinder 20 axis, passages and valves thereon for admitting high-pressure steam to the lower end of the smaller steam cylinder, for leading the steam exhausted from the lower end of said cylinder to the lower end of the 25 larger steam cylinder, and for discharging the steam exhausted from the lower end of the last mentioned cylinder respectively, mechanism for actuating all of said valves in coördination with one another, and passages for affording open communication between the upper ends of the respective steam cylinders, and the exhaust passages from the lower end of said cylinders at points beyond the respective exhaust valves. 30
9. In a steam hydraulic intensifier, the combination with a pair of hydraulic elements comprising a hydraulic cylinder and a ram adapted to coöperate therewith, the members of said pair having their common 35 axis arranged vertically and the one member being stationary while the other is adapted to perform its working stroke in the upward direction, of steam cylinders of relatively large and relatively small diameter 40 mounted in axial alinement with one another and with the members of the pair of hydraulic elements, single-acting pistons fitted to reciprocate in the respective steam cylinders, an axially-extending piston-rod attached to both of said pistons, a crosshead on the movable member of the pair of hydraulic elements, rods attached eccentrically to one of the steam pistons and to said crosshead and extending parallel to the cylinder axis, 45 passages and valves thereon for admitting high-pressure steam to the lower end of the smaller steam cylinder, for leading the steam exhausted from the lower end of said cylinder to the lower end of the larger steam cylinder, and for discharging the steam exhausted from the lower end of the last mentioned cylinder respectively, a single handing-lever and mechanism connected therewith for controlling all of 50 said valves, an upright cam-bar attached to said crosshead and having one edge inclined to the direction of movement of the bar, and a lever adapted to bear against said inclined edge and coupled to the handing-lever through said connected mechanism, for causing the supply of steam to both steam cylinders to be cut off during each working stroke of the intensifier at a point corresponding to the angular position wherein for the time being the handing-lever is held. 55
11. In a hydraulic intensifier operated by elastic motive fluid, the combination of a pair of hydraulic elements comprising a hydraulic cylinder and a ram adapted to coöperate therewith; a pair of elastic fluid cylinders of relatively large and relatively small diameter respectively; individual pistons fitted to reciprocate in the respective elastic fluid cylinders, a connection whereby 60 said pistons are coupled to one another and means connecting said pistons to the movable member of said pair of hydraulic elements for causing said member to move as one with the pistons; passages and valves 65 thereon severally for admitting elastic motive fluid at the maximum working pressure to the cylinder of smaller diameter, for leading the motive fluid discharged from said cylinder to the cylinder of larger di- 70 75 80 85 90 95 100 105 110 115 120 125 130
- 65 automatically-acting hunting-gear actuated by the movement of the steam pistons and adapted to coöperate with said handing-lever and connected mechanism, for causing the supply of steam to both steam cylinders to be cut off during each working stroke of the intensifier at a point corresponding to the angular position wherein for the time being the handing-lever is held. 70

ameter and, alternatively, to exhaust, for admitting elastic motive fluid at the maximum working pressure to the cylinder of larger diameter, for leading the motive fluid discharged from said cylinder to exhaust, and mechanism for actuating all of said valves in coördination with one another.

12. In a hydraulic intensifier operated by elastic motive fluid, the combination of a pair of hydraulic elements comprising a hydraulic cylinder and a ram adapted to co-operate therewith; a pair of elastic fluid cylinders of relatively large and relatively small diameter respectively; pistons fitted to reciprocate in the respective elastic fluid cylinders and coupled to one another and to the movable member of said pair of hydraulic elements for causing said member to move as one with the pistons; passages and valves thereon severally for admitting elastic motive fluid at the maximum working pressure to the cylinder of smaller diameter, for leading the motive fluid discharged from said cylinder to the cylinder of larger diameter and, alternatively, to exhaust, for admitting elastic motive fluid at the maximum working pressure to the cylinder of larger diameter, for leading the motive fluid discharged from said cylinder to exhaust, mechanism for actuating all of said valves in coördination with one another, and means for causing the admission of elastic motive fluid at the maximum working pressure to the cylinder of larger diameter to take place automatically on the pressure in the hydraulic cylinder exceeding a predetermined limit.

13. In a hydraulic intensifier operated by elastic motive fluid, the combination with a pair of hydraulic elements comprising a hydraulic cylinder and a ram coöperating therewith, of a plurality of cylinders, pistons reciprocating in said cylinders and connected with each other, means whereby the movable member of said pair of hydraulic elements is connected with said pistons, connections for conducting motive fluid to said cylinders, a normally closed valve in at least one of said connections whereby the admission of motive fluid to the connected cylinder is controlled and means whereby

said valve is automatically opened when the hydraulic pressure reaches the maximum.

14. In a hydraulic intensifier operated by elastic motive fluid, the combination with a pair of hydraulic elements comprising a hydraulic cylinder and a ram coöperating therewith, of a plurality of cylinders, pistons reciprocating in said cylinders and connected with each other, means whereby the movable member of said pair of hydraulic elements is connected with said pistons, connections for conducting motive fluid to said cylinders, a normally closed valve in at least one of said connections whereby the admission of motive fluid to the connected cylinder is controlled, means whereby said valve is automatically opened when the hydraulic pressure reaches the maximum and manually operated means whereby said valve may be actuated independently of its automatic actuation.

15. In a hydraulic intensifier operated by elastic motive fluid, the combination with a pair of hydraulic elements comprising a hydraulic cylinder and a ram coöperating therewith, of a plurality of cylinders located in coöperative relation, pistons in said cylinders coupled to one another and to the movable member of said pair of hydraulic elements whereby said pistons and movable member are concurrently operated, a conduit leading from the exhaust end of one of said cylinders to the inlet end of another of said cylinders, an exhaust pipe connected with said conduit, a valve in said conduit for controlling the passage of motive fluid and another valve also in said conduit for opening the exhaust pipe on the return stroke of the piston in said cylinder, an exhaust connection at the opposite end of said cylinder, a line for the admission of motive fluid to the first named cylinder, an exhaust pipe connected therewith, a valve in said line for controlling the passage of said motive fluid and another valve also in said line for opening the exhaust pipe on the return stroke of the piston in said cylinder and mechanism for actuating all of said valves in coördination with one another.

THOMAS WILTON HAND.
